UNITED STATES PATENT OFFICE.

LIPA POLINKOWSKY, OF ANTWERP, BELGIUM, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed January 19, 1922. Serial No. 530,244.

To all whom it may concern:

Be it known that I, LIPA POLINKOWSKY, a citizen of Russia, residing at 14 Rue de Bastion, Antwerp, Belgium, have invented 5 certain new and useful Improvements in Telephone-Exchange Systems, of which the following is a full, clear, concise, and exact description.

This invention relates to telephone exchange systems and more particularly to systems employing machine switching apparatus for the establishment of talking connections.

The central offices, where the switching 15 operations are performed in the extension and completion of connections between subscribers' lines, serve not only their own respective areas in the exchange but also co-operate with each other in disposing of calls 20 received for outlying areas. A call incoming to a given office either from a local line or from a distant calling office may be one of two general classes as regards its destination. It may in one case be intended for 25 a local subscriber's line, wherefore a group selector switch, to which the connection is first extended, selects a local switch through which the call is routed to the local subscriber's line. In the other instance the 30 call may be destined for a distant office, in which event the group selector, instead of choosing a local switch, selects an outgoing interoffice trunk to the distant called office, whereafter selective switches in said called 35 office are set to complete the connection.

The usual method is to control the automatic selective switches, employed for establishing local and interoffice connections as above outlined, by means of a sending device located at some convenient point near where the call originates. It may be a sender provided at the subscriber's station or one located at the central office according to the character of the switches it controls. 40 The control is exercised over a circuit which extends from the sender to the switches in succession as the connection progresses. As will be obvious, the length of this control circuit may vary between wide limits in 45 systems such as those mentioned above where both local and interoffice service is given.

The object of this invention is to make provision for discriminating between the 50 different classes of calls that are extended

and to vary the character of the switch control circuits to suit the particular call involved.

A feature of the invention relates to an arrangement wherein a selective switch, 60 adapted to extend connections of different classes, is capable of determining the class of any particular connection and to in turn determine the preparation of the proper kind of a controlling circuit for governing the 65 selective operations of the succeeding switches.

Such other features and advantages as are contemplated by this invention will become thoroughly understood from the following description and from the appended 70 claims.

In the drawing Figs. 1, 2, 3 and 4 when taken in proper order illustrate in detail a telephone exchange system of the character 75 to which the principles of this invention are applicable.

Figs. 1, 2 and 4 when taken in order from left to right illustrate a connection established between a subscriber's line in an originating office and a subscriber's line terminating locally in a second or tandem office.

In Fig. 1 there is illustrated schematically to the left of the broken vertical line the first or originating office in which a subscriber's line terminates and also in which a register controlling sender is located. To the right of the vertical broken line is shown a first group selector switch located in the second or tandem office and in which the 80 incoming trunk from the originating office terminates.

Fig. 2 shows a local second group selector switch in the tandem office to which connections are extended through the terminal 85 bank of the first group selector.

Fig. 4 shows a final selector switch located in the tandem office and which has access to local subscribers' lines.

Figs. 1, 3 and 4 when taken in the order 10 named illustrate a connection established from the calling subscriber's line at the originating office through the tandem office and thence over an interoffice trunk line to a distant office to a called subscriber's line.

In Fig. 3 the group selector switch there shown is one in which the interoffice trunk incoming from the tandem office terminates. This group selector switch, which is located 11 in the distant or called office, has access to

final switches such as the one shown in Fig. 4 which in turn have access to the called subscriber's line.

It has been chosen to illustrate in this application a telephone exchange system involving three central offices. A subscriber in the first central office such as the subscriber of line 100 may establish a connection with a subscriber's line in the second office and to do so he initiates the call in the regular way bringing about the association of the central office register sender 101 with his line. He then transmits the proper series of impulses to cause the registers of the sender 101 to take up settings corresponding to the designation of the wanted line. Two of these registers 104 and 105 are illustrated. The register sender then becomes effective to cause the selective operation of a group selector switch, the brushes of which are shown at 108 and 109, to choose a trunk line 110, 111 leading to the second office and there terminating in a first group selector switch 180. Following this operation the group selector switch 180 is controlled over the trunk 110, 111 by the register sender in the originating office to select a trunk such as trunks 166, 167, 168 leading to local second group selector 230, shown in Fig. 2. Thereafter the second group selector switch 230 is selectively controlled to choose an idle final selector switch 440 in the group having access to the subscriber's line 430 local to the second office. Lastly, the final selector switch is operated to choose the called line.

Again the calling subscriber in the originating office may establish a connection to a called subscriber's line which belongs to a distant called office accessible through the second office, which in this case serves as the tandem point. In this event the calling subscriber initiates the call in substantially the same manner and causes the record of the wanted subscriber's line to be registered on the register sender 101 in the originating office. Also in a similar manner the selector switch 108, 109 is controlled to extend the calling line to the first group selector switch 180 in the tandem office. At this point the operation differs inasmuch as the group selector switch 180 is now selectively controlled to choose an outgoing two-wire interoffice trunk such as the trunk 169, 170 leading to the distant called office and there terminating in a group selector switch 330, indicated in Fig. 3. The group selector switch 330 is thereupon controlled over the extended connection from the register mechanism 101 to select an idle final switch similar to 440 which in turn is selectively controlled to complete the establishment of the connection to the called subscriber's line.

Inasmuch as the switch control circuit, which extends from the register sender 101 to the successive selector switches in the

process of building up a connection, may vary considerably in its length, it is advisable to make some provision for insuring the same degree of satisfactory operation when control is exercised over a long circuit as when the switch is being controlled over a comparatively short circuit. In the particular type of switch shown in this application the control of the selective movement is accomplished by the use of revertive impulses. That is to say the switch is set in operation and by its movement causes impulses to be reverted over the control circuit back to the sender which receives the impulses and measures the permissible extent of operation of the switch in accordance with the registration of the sender. So far as the idea of insuring a satisfactory operation of the switch is concerned, the invention might equally as well be applied to systems of the character wherein impulses are sent directly to determine the selective movement such as shown in the patent to Goodrum, No. 1,231,013, issued June 26, 1917. In order to attain the desired result, the first group selector switch 180 in the second office is adapted to distinguish, during its selective movement, between the calls of one class and calls of another class. If the selector switch 180 is operated to extend a connection over a local trunk to the second group selector switch 230 it determines this fact and accordingly prepares a fundamental control circuit which extends over a plain metallic path to the selector switch 230 whereby the register sender 101 may control this latter switch. However, should the group selector switch 180 be operated to select an interoffice trunk leading to the distant switch 330 it also determines this fact and prepares the incoming fundamental control circuit from the register sender and the outgoing fundamental control circuit to the distant switch 330 in such a manner that impulses reverted from the said switch 330 during its operation are repeated from the switch 180 back to the register sender 101. By means of this repeating fundamental circuit the impulses created at the switch and reverted back to the tandem office are reproduced at the tandem office and transmitted therefrom to the register sender 101, thus insuring a greater degree of accuracy in the control between the register sender and the distant selector switch.

The selector switches employed in this system are of the rotary power driven type in which a plurality of sets of brushes are provided and which are selectively tripped into operative engagement with the terminal bank during the rotation of the brush shaft. A switch of this general character is illustrated and described in the patent to Mc-Berty No. 1,097,868, issued May 26, 1914.

The selective switches are arranged to be

controlled by a central office sender which consists of a plurality of sequence switch registers adapted to receive the designation impulses of a called line and to in turn 5 control the successive switches over a fundamental circuit in accordance with the registrations on the registers. A register control device of the general character suitable for operation in connection with the system 10 illustrated is shown and described in my Patent No. 1,365,269, issued January 11, 1921.

The establishment of a local connection.

A description will now be given in detail 15 of the operation of the system when connection is established between the subscriber's line 100 in the originating office and a local subscriber's line 430 terminating in the second office. The subscriber of line 100 upon 20 initiating the call causes the operation of a line finder or line switch in the well-known manner to extend his line through to the first group selector switch 108, 109 whereupon the register sender 101 is associated. The subscriber then transmits impulses over the line to set the successive 25 registers 104, 105, etc. to record the designation of the called subscriber's line 430. Following this the brushes 108, 109 of the 30 group selector are set under the control of the sender 101 on the terminals of the trunk line 110, 111 leading to the group selector switch 180 in the second office.

Upon the selection of the group selector 35 switch 180 the fundamental circuit is established from battery through the winding of relay 117, upper left contact 135 (1+1½), back contact and middle right armature of relay 112, conductor 111, brush 109, contact 40 107, armature and contact of relay 103, winding of the stepping relay 102, contact 171, contact 106, brush 108, conductor 110, upper contact 124 (1+13), upper contact 128 (1+2), left back contact of relay 112 45 to ground. Relay 117 becomes energized and closes the circuit from battery to the resistance 145, lower right contact 130 (1+5¾), lower left contact 130 (1+17), winding of relay 115, left front contact of 50 relay 117, upper right contact 172 (1) to ground. Also a circuit is closed from battery through the upper contact 133 (1+12), lower left contact 133 (1+4) windings of relay 114, upper right contact 123 (1+1½), lower left contact 123 (1+1½), left front 55 contact of relay 117 to ground through the contact 172. Relays 115 and 114 become energized and lock over circuits as above traced through the windings of said relays 60 and thence to the lower left and upper right contact 123 respectively and therefrom over the conductor 173 to ground at the armature of relay 114. In other words, the relays 115 and 114 remain locked until sequence 65 switch 120 leaves position 1½ to open its

upper right and lower left contacts 123. With relay 115 energized a circuit is established from battery through the winding of the magnet of sequence magnet switch 120, lower right and upper left contacts 137 70 (1), front contact of relay 115, lower right contact 172 (1+6) to ground. Sequence switch 120 advances out of position 1 and into position 2 and relays 115 and 114 become deenergized. Before the upper left 75 contact 135 opens as sequence switch 120 passes out of position 1½ the lower left contact 135 is closed in position 1¾ and the relay 117 remains energized in the fundamental circuit as follows: battery through the 80 winding of relay 117, lower left contact 135 (1¾+2), outer right contact of relay 117 and thence over the fundamental circuit as previously traced to ground at the left back contact of relay 112.

With relay 117 energized in position 2 of sequence switch 120 a circuit is completed from battery through the trip spindle power magnet 121, lower right contact 140 (2), inner right front contact of relay 117 to 90 ground. The trip spindle magnet 121 rotates the trip spindle to select the proper set of brushes to be rendered active during the subsequent rotation of the brush carriage.

Upon leaving its normal position the trip spindle causes the interrupter brush 143 to move to disengage the comparatively deep notch thereby forcing it into contact with the interrupter spring 142. Although the 95 spring 143 encounters a notch at each 100 brush tripping position the depth of this notch is not sufficient to permit said spring to disengage the spring 142. Consequently, springs 142 and 143 remain in contact with each other until the trip 105 spindle again reaches normal. During the time that the trip spindle is rotated from one tripping position to another, the spring 143 is forced upwardly to a sufficient extent to cause spring 142 to engage the spring 110 141, but when the tripping spindle is in one of its tripping positions the spring 143 falls into a shallow notch and permits the springs 141 and 142 to disengage.

While the tripping spindle is passing 115 from one brush tripping position to another a circuit is closed as follows: From battery through the winding of relay 117, lower left contact 135 (1¾+2), interrupter 120 springs 141, 142 and 143 to ground. This circuit maintains the relay 117 energized and shunts out the stepping relay 102 in the fundamental circuit. The stepping relay 102 serves in the well-known manner to restore to its normal position the register 125 which represents the amount of movement to be taken by the group selector switch 180 in selecting the proper set of brushes. The fundamental circuit is opened by means of a relay 103 at the sender at the end of selec- 130

- tion. As soon following the opening of the fundamental circuit at the sender as the tripping spindle reaches its next brush tripping position springs 141 and 142 become separated and the holding circuit of relay 117 is opened. Relay 117 becomes deenergized and in so doing severs the circuit of the trip spindle power magnet 121 whereby the trip spindle ceases to rotate.
- 10 Moreover, relay 117 upon deenergizing closes a circuit from ground through its middle right back contact, lower right contact of spring 139 (2+4), winding of sequence switch magnet 120 to battery. Sequence switch 120 leaves position 2.
- 15

- As sequence switch 120 reaches position 2 $\frac{3}{4}$ a circuit is closed from battery through the winding of relay 117, upper right contact 135 (2 $\frac{3}{4}$ +4), back contact of relay 118, 20 lower left contact 134 (2+3 $\frac{1}{2}$), back contact of relay 115, lower right contact 172 (1+6) to ground. Relay 117 becomes energized and opens the circuit of sequence switch 120 permitting said sequence switch 25 to stop in position 3. With sequence switch 120 in position 3 and the relay 117 operated a circuit is closed over the brush carriage power magnet 122 traceable from battery to the winding of said magnet, upper right contact 140 (3), inner right front contact of relay 117 to ground. The power magnet 122 operates to cause the brush carriage to rotate tripping the selected set of brushes and trailing the same over the terminals of 30 35 the corresponding level in the contact bank.

- Since the call is one to a local subscriber's line the level chosen by the group selector switch 180 contains the terminals of trunks which lead to local selector switches such as the switch 230. The first set of terminals 146, 147 and 148 in one of these local levels is left blank with the exception of the test terminal 148 which is wired as 40 illustrated to the lower right contact 123, closed in position 3. Following this first set of terminals the succeeding sets of terminals such as sets 149, 150, 151 and 152, 153, 154, etc. represent local trunk lines.

- When the tripped set of brushes 161, 162, 50 163 commences to rotate under the influence of the power magnet 122 they first encounter the terminals 146, 147, 148. A circuit is thereupon established from battery through the upper right contact 133 (1+12), lower left contact 133 (1+4), windings of relay 114, upper right contact 123 (3+4), lower right contact 123 (3), terminal 148, brush 163, upper left contact 132 (3), left-hand winding of test relay 118 to ground. The 55 60 65 resistance of the windings of relay 114 is such as to prevent the energization of relay 118 in the circuit traced. Relay 114, however, operates and locks in a circuit from battery as above traced through its windings to the upper right contact 123

(3+4) thence over conductor 173 to ground. The brush carriage continues to rotate and thereafter the brushes 161, 162 and 163 engage terminals of trunk lines leading to the local selector switches. When a set of terminals representing an idle trunk 166, 167, 168 is encountered a sufficiently high potential is found on the test terminal 151 to permit the energization of the test relay 118. The circuit for the energization of this relay may be traced from battery through the winding of relay 203, and also in parallel from battery through contact 204 (1+10) of sequence switch 210, conductor 168, terminal 151, brush 163, upper left contact 132 (3), left-hand winding of relay 118 to ground. Relay 118 becomes operated and opens the above traced circuit for relay 117 which thereupon deenergizes and in turn opens the circuit of the power magnet 122. The brush carriage comes to rest with the brushes 161, 162, 163 on the terminals 149, 150, 151 of the trunk 166, 167, 168. Relay 118 also closes a circuit over the test conductor through its right-hand low resistance winding and front contact, lower left contact 134 (2+3 $\frac{1}{2}$), back contact of relay 115, lower right contact 172 (1+6) to ground. Relay 118 thereby shunts out its left high resistance winding and in so doing 70 75 80 85 90 95 100 105 110 reduces the potential on the test terminal 151 to such an extent as to render the selected trunk busy to other switches. When relay 117 becomes deenergized it closes the circuit from ground through its inner right back contact, lower right contact 139 (2+4), winding of sequence switch magnet 120 to ground. Sequence switch 120 leaves position 3 and moves into position 5. When sequence switch 120 reaches position 3 $\frac{3}{4}$ the above traced holding circuit through the right-hand winding of relay 118 is modified so as now to extend to ground through upper right contact 134 (3 $\frac{3}{4}$ +16).

115 120 125 130 While sequence switch 120 is passing through position 4 a circuit is closed for the energization of relay 112 due to the fact that relay 114 is energized at this time. It will be observed that relay 114 is energized by reason of the fact that the selector switch 180 was operated to choose a group of trunks leading to local switches. A circuit for the energization of relay 112 may be traced from battery through the right-hand winding of said relay, upper left and lower right contacts 129 (4), left back contact of relay 117, conductor 174, lower left contact 123 (4), conductor 173 to ground at the contact of relay 114. Relay 112 becomes energized and closes a circuit from battery through the winding of relay 116, upper right contact 127 (1 $\frac{3}{4}$ +13), left-hand winding and left front contact of relay 112 to ground. Relay 116 becomes energized and

relay 112 remains energized in this circuit after sequence switch 110 has passed into position 5. The relay 112 by being energized at this time extends the fundamental circuit 5 incoming over the trunk conductor 110, 111 directly through to the second local group selector switch 230 over an uninterrupted metallic path. Sequence switch 120 passes out of position 4 and the holding circuit of 10 relay 114 is opened and this relay becomes deenergized. In position 5 of sequence switch 120 a circuit is closed from battery through the winding of said sequence switch, lower right contact 138 (5+11), 15 contact of relay 116, upper left contact 172 (3+13) to ground. Sequence switch 120 is energized in this circuit and moves over position 11 and into position 13.

The fundamental circuit is now closed 20 through to the second selector switch 230 ready for controlling the selective movement of this switch. Said fundamental circuit may be traced from battery through the winding of relay 202, contact 200 (1+2), 25 conductor 167, terminal 150, brush 162, left back contact of relay 113, middle right contact of relay 112, conductor 111, thence through the stepping relay 102 as previously traced and returning by way of conductor 110, upper contact 124 (1+13), innermost right contact of relay 112, brush 161, terminal 149, conductor 166 to ground at contact 201 (1+2). Relay 202 becomes energized and closes a circuit from battery 30 through the winding of sequence switch magnet 210, upper contact 212 (1), front contact of relay 202 to ground, driving said sequence switch out of position 1 and into position 2. In position 2 brush selection 35 takes place and a circuit is closed for the brush tripping magnet 206 from battery through the winding of said magnet, left contact 229 (2), front contact of relay 202 to ground. The brush tripping spindle is 40 rotated and for each brush tripping position a circuit is closed from battery through the winding of relay 202, contact 231, interrupter springs 207, 208 and 209 to ground. This circuit maintains the relay 202 operated and shunts out stepping relay 102 of 45 the sender.

When the proper set of brushes have been selected the sender opens the fundamental circuit and immediately thereafter springs 50 207 and 208 become separated to open the substitute circuit for relay 202. Relay 202 deenergizes and opens the circuit of the trip spindle magnet 206. Relay 202 also closes a circuit from battery through the winding 55 of sequence switch 210, upper contact 211 (2+3), back contact of relay 202 to ground. The sequence switch 210 is advanced from position 2 into position 5.

In position 5 the brush carriage power magnet 216 is energized in a circuit from 60

battery through the winding of said magnet, lower contact 214 (5+6), back contact of test relay 215 to ground. The brush carriage is rotated to move the selected set of brushes 223, 224, 225 over the terminals of 70 the contact bank in the trunk hunting operation. When an idle trunk is found test brush 225 encounters a high potential on the test terminal 228 and the switch comes to rest. The test circuit may be traced from 75 battery through the winding of relay 401, and also in parallel from battery through the contact 412, thence over terminal 228, brush 225, left contact 218 (5), right-hand high resistance winding of relay 205 to 80 ground. The potential being high relay 205 is operated and immediately closes a circuit through its left-hand winding and contact and the winding of relay 215 to ground. This latter circuit is sufficiently 85 low in resistance to reduce the potential on terminal 228 and its multiples whereby the final selector switch 440 is rendered non-selectable to other switches. Immediately 90 after relay 215 is operated the circuit of the power magnet 216 is opened, stopping the brush carriage. Relay 215 also closes a circuit from battery through the winding of sequence switch magnet 210, upper contact 212 (5+7), front contact of relay 215 95 to ground. Sequence switch 210 moves out of position 5 over position 6 and into position 8. In position 8 the sequence switch 210 finds a circuit through the lower contact 212 and continues to advance into position 10. On reaching position 9 the test circuit leading from the final selector switch through terminal 228 and brush 225 is now closed through the right contact 218 (9+10) and the winding of relay 215 to ground. 100 This modified circuit shunts out the relay 205 permitting the same to become deenergized.

When the sequence switch 210 of the second group selector is in position 10 the 110 fundamental circuit is completed for controlling the final selector switch 440. This circuit may be followed from battery through the winding of relay 400, left contact 422 (1+5), terminal 227, brush 224, 115 lower contact 219 (9+10), conductor 167, thence as previously traced through the stepping relay at the sender and returning by way of conductor 166, upper contact 220 (10), brush 223, terminal 226, left contact 421 (1+5), to ground. Relay 400 now operates and closes a circuit from ground through its front contact, right contact 413 (1), winding of sequence switch magnet 410 to battery. Sequence switch 410 moves out 120 of position 1 and into position 2. In this position the trip spindle magnet 405 is energized in a circuit from battery through the winding of said magnet, lower contact 431 (2), front contact of relay 400 to ground. 130

The tripping spindle is rotated to select the proper set of brushes determined by the registration at the sender and for each brush tripping position passed over a circuit is closed from battery through the winding of relay 400, lower contact 429 (2+5), interrupter springs 406, 407 and 408 to ground. This circuit holds the relay 400 operated and shunts out the stepping relay 102 at the sender. When the proper set of brushes has been reached the fundamental circuit is opened at the sender and shortly thereafter, when springs 406 and 407 are opened, the relay 400 becomes deenergized 10 to open the circuit of the trip spindle magnet 405. Also, the relay 400 completes a circuit from ground through its back contact, upper right contact 432 (2+5), winding of sequence switch 410 to battery. Sequence switch 410 leaves position 2. Before said sequence switch can reach position 5, however, the fundamental circuit as previously traced is again completed at the sender and relay 400 becomes energized to open 20 the driving circuit of the sequence switch. Therefore, the sequence switch 410 stops in position 5 where a circuit is closed for the power magnet 404. This circuit may be traced from battery through the winding of 30 said power magnet, lower contact 414 (5), front contact of relay 400 to ground.

The power magnet 404 causes the brush carriage to rotate carrying the selected set of brushes 425, 426, 427 over the terminals of the selected level of called subscribers' lines. For each set of terminals passed the interrupter springs 433, 434 are closed and a circuit is completed from battery through the winding of relay 400, lower contact 429 (2+5), springs 433 and 434 to ground. This circuit shunts out the stepping relay 102 in the fundamental circuit and causes the restoration of the control register to its normal position. When the brushes of the final selector reach the terminals of the called subscriber's line 430, the sender opens the fundamental circuit and immediately thereafter springs 433 and 434 are separated to open the substitute circuit of relay 400. Relay 50 400 releases its armature, opens the circuit of the power magnet 404 and closes a circuit for driving sequence switch 410 out of position 5. This latter circuit is traceable from ground through the back contact of relay 400, upper right contact 432 (2+5), the winding of sequence switch magnet 410 to battery.

Before proceeding with the testing and ringing operations a description will be 60 given of the manner in which the preceding group selector switches 180 and 230 are advanced into their talking positions at this time. As sequence switch 410 leaves position 5 the contact 412 is opened thereby increasing the resistance included in the test

circuit. This increase of resistance reduces the current to such an extent that relay 215 is unable to maintain its armature attracted. Relay 215 on releasing closes a circuit from ground through its back contact, upper contact 214 (10), winding of sequence switch 210 to battery. Sequence switch 210 leaves position 10 and advances into position 15, which is the talking position of the sequence switch. 75

As sequence switch 210 leaves position 10 the contact 204 is opened whereby the resistance in the test circuit extending back to the first group selector switch is also increased. In response to this increase of resistance the relay 118 releases its armature and a circuit is established from battery through the winding of sequence switch magnet 120, upper left contact 139 (13), back contact of relay 118, upper right contact 134 (33/4+16), to ground. Sequence switch 120 leaves position 13 and moves into position 14. 80

At this time, which is subsequent to the completion of the final units selection, the group selector 108, 109 having advanced to its talking position opens the lower left contacts 106, 107, and closes the upper left contacts 106, 107, the register sender 101 at the originating office is therefore disassociated from the connection and a circuit established through from the calling subscriber's line over trunk 110 and 111 in the usual manner. Consequently, if at the time the sequence switch 120 reaches position 14, the calling subscriber still has its receiver off the switch-hook the relay 114 is energized from a source of current at the group selector switch in the originating office. The circuit for relay 114 leads from battery at the upper left contact 107 over the trunk conductor 111, middle right back contact of relay 112, lower left contact 126 (133/4+16), windings of relay 114, inductance coil 175, lower contact 124 (14+16), and thence over the other side of trunk 110 to ground at the upper life contact 106. It will be noted that relay 112 and relay 116 become deenergized as sequence switch 120 left position 13. With relay 114 operated a circuit is closed from battery through the winding of relay 117, lower left contact 136 (14+16), contact of relay 114 to ground. Relay 117 becomes energized and closes a circuit from ground through its inner right front contact, lower left contact 139 (14+15), winding of sequence switch magnet 120 to battery. Sequence switch 120 moves from position 14 into position 16 which is the talking position thereof. 105

When relay 118 becomes deenergized as sequence switch 210 leaves position 10 and until sequence switch 120 arrives in position 15 the circuit of relay 203 is held opened. Relay 203 is slow to release, however, and does not retract its armature during this in- 110 115 120 125 130

terval. When sequence switch 120 moves into position 15 relay 203 is maintained energized in a circuit leading over the test conductor 168 and thence through the upper 5 left contact 132 (15+17) and the left-hand high resistance winding of relay 118 to ground. When sequence switch 120 later reaches position 16, the left-hand winding of relay 180 is shunted by the closure of the 10 lower right contact 132. Hence, relay 203 remains energized and relay 118 remains de-energized.

In position 6 of sequence switch 410 a circuit is closed from battery through the 15 winding of relay 400, left contact 416 (6+7) to ground. Relay 400 operates and closes a circuit from ground through its front contact, right contact 413 (6), winding of sequence switch magnet 410 to battery, driving 20 said sequence switch out of position 6 and into position 10. As sequence switch 410 is passing through position 8 it closes a test circuit to test the condition of the called subscriber's line 430. The test circuit may be 25 traced from the test terminal 436, test brush 427, left-hand high resistance winding of relay 403, right contact 416 (8) to ground. Assuming the called line 430 to be idle, the 30 current flowing from battery through the winding of cut-off relay 428 of the test terminal 436 is sufficient to cause the energization of the test relay 403. Relay 403 operates and closes a circuit through its right-hand low resistance winding, armature contact, winding of relay 402, front contact of 35 relay 401 to ground. This low resistance circuit reduces the potential on the multiples of test terminal 436, rendering the called line busy to other final switches. Relay 402 40 operates and closes a circuit from ground through the back contact of relay 400 (this relay having deenergized when sequence switch 410 left position 7), front contact of 45 relay 402, lower right contact 432 (6+11), winding of sequence switch 410 to battery. Thereafter sequence switch 410 continues to move through positions 10 and 11 and into position 12.

In position 12 a circuit is closed from the 50 ringing source 419, right contact 418 (12+13), brush 426 over the called subscriber's line and returning by way of brush 425, upper contact 423 (12+14), winding of relay 420 to battery. Ringing current is 55 thereby immediately applied to the called subscriber's line. The relay 420 being marginal does not operate at this time. Immediately after the sequence switch 410 enters position 12 a circuit is closed from battery 60 through the winding of relay 400, left contact 415 (12) to the brush of interrupter 437. When this brush closes on a metallic segment of the interrupter, relay 400 operates and completes a circuit from ground 65 through its front contact, lower right con-

tact 413 (11+14), winding of sequence switch magnet 410 to battery. Sequence switch 410 moves out of position 12 and moves into position 13 where it comes to rest since the contact 415 (12) opens the circuit 70 of relay 400 before sequence switch 410 can move out of position 13. At the end of a definite interval following the arrival of sequence switch 410 in position 13, a second interrupter 438 is closed to establish a circuit 75 over contact 417 for relay 400. Relay 400 operates again and closes the circuit traced over sequence switch 410 which moves out of position 13 and into position 14. In position 14 the source of initial ringing current 80 is disconnected and the ringing machine 439 is rendered effective to intermittently apply ringing current to the called line 430.

When the called subscriber responds by 85 removing his receiver from the switchhook, the resistance in the loop of his line is so reduced that the marginal relay 420 becomes energized. Relay 420 closes a circuit by way of contact 413 for driving sequence switch 410 out of position 14 and into position 15, 90 which is the talking position. As sequence switch 410 reaches position 15 to establish the talking connection through the final selector and with the called subscriber's receiver off the switchhook a circuit is closed 95 for supplying talking current to the called line from the first group selector switch 180. This circuit may be traced from battery through the winding of relay 116, lower right contact 127 (16), outermost right contact of relay 112, left back contact of relay 113, brush 162, terminal 150, conductor 167, upper contact 219 (13+15), brush 224, terminal 227, upper contact 424 (15), brush 426, thence over the loop of the called line 100 430, brush 425, lower contact 423 (15+17), terminal 226, brush 223, lower contact 220 (13+15), conductor 166, terminal 149, brush 161, lower left contact 125 (16+17), impedance coil 119, conductor 173, to ground 105 at the contact of relay 114. Relay 116 operates and modifies the talking circuit extending from the originating office by excluding the right-hand high resistance winding of relay 114. The talking circuit 110 may now be traced over the trunk conductor 111, middle right back contact of relay 112, lower left contact 126 (13 $\frac{3}{4}$ +16), upper left contact 126 (16), front contact of relay 116, upper left contact 138 (16), left-hand winding of relay 114, impedance coil 175, lower right contact 124 (14+16), and thence over conductor 110, back to the opposite pole of battery. Talking current between the originating office and the called office is, therefore, supplied through the left-hand winding of relay 114 and the impedance coil 175, while talking current for the called subscriber's line is supplied from the winding of relay 116 and the impedance coil 119. The 115 120 125 130

two branches of the talking circuit are separated by the condensers 176 and 177. Due to the exclusion of the right-hand high resistance winding of relay 114 at the response 5 of the called subscriber, the resistance in the circuit leading back to the originating office is materially reduced and this principle may be utilized for any desired purpose such as controlling a message register or supervisory signal.

At the termination of conversation the subscribers replace their receivers on the switchhooks and relays 114 and 116 and 117 become deenergized. Relay 117 closes a circuit from ground through its inner back contact, lower right contact 139 (16), winding of sequence switch magnet 120 to battery. Sequence switch 120 moves out of position 16 and into position 17. In position 15 20 a circuit is closed from battery through the winding of relay 117, upper right contact 135 (16 $\frac{3}{4}$ +18), back contact of relay 118, lower right contact 134 (16+17), springs 142 and 143 to ground. Relay 117 25 operates and closes a circuit from battery through the trip spindle power magnet 121, lower right contact 140 (17), inner front contact of relay 117 to ground. The trip spindle is rotated back to its normal position 30 where the interrupter spring 143 enters the deep notch and causes its separation from spring 142. Relay 117 thereupon becomes deenergized and opens the circuit of the magnet 121 and also closes a circuit from 35 ground through its inner right back contact, lower left contact 129 (17+18), upper right contact 129 (16+17), inner right back contact of relay 113, winding of sequence switch magnet 120 to battery. Sequence switch 40 40 120 moves into position 18 where the brush carriage is restored to its normal condition. Relay 117 is operated in a circuit from battery through the winding thereof, upper right contact 135 (16 $\frac{3}{4}$ +18), left back contact of relay 118, upper right contact 134 (17 $\frac{3}{4}$ +18) to ground. Relay 117 closes a 45 circuit from battery through the brush carriage power magnet 122, upper right contact 140 (18), inner right front contact of relay 117 to ground. When the brush carriage 50 has been fully restored a circuit is closed from battery through the home contact 165, brush 164, upper right contact 132 (17+18 $\frac{1}{4}$), left-hand winding of relay 118 55 to ground. Relay 118 attracts its armature and opens the circuit of relay 117 which in turn deenergizes and opens the circuit of the brush carriage power magnet 122. Relay 117 also closes a circuit from ground 60 through its inner right back contact, lower right contact 139 (18), winding of sequence switch magnet 120 to battery, driving said sequence switch into its normal position, 1.

Sequence switch 120 on leaving position 65 17 opens at its contact 132 the holding cir-

cuit of relay 203 of the second group selector switch. Relay 203 deenergizes and completes a circuit from ground through contact 213 (10+16), winding of sequence switch 210 to battery. Sequence switch 210 70 moves out of position 15 and into position 17. In position 17 the brush carriage is restored to its normal position by means of a circuit from battery through the power magnet 216, lower contact 214 (17), back contact 75 of relay 215 to ground. When the brush carriage is fully restored, a circuit is closed from battery through the contact 217 (16+18), home contact 222, brush 221, winding of relay 215 to ground. Relay 215 80 operates and opens the circuit of the power magnet and closes a circuit from ground through its front contact, upper contact 212 (15+18), winding of sequence switch magnet 210 to battery. Sequence switch 210 85 thereupon moves into position 1. It will be noted that the trip spindle of the second group selector switch restores to its normal position as soon as the sequence switch 210 reaches position 8. The circuit for causing 90 its restoration is traceable from battery through the magnet 206, right contact 229 (8+1), interrupter springs 208 and 209 to ground.

Sequence switch 210 on leaving position 95 15 opens the holding circuit of relay 401. This relay becomes deenergized and completes a circuit from ground through its back contact, upper contact 409 (12+16), winding of sequence switch magnet 410 to 100 battery. Sequence switch 410 advances out of position 15 and into position 17. In position 17 a circuit is closed from battery through the winding of sequence switch magnet 410, upper right contact 432 (17), back contact of relay 400 to ground and sequence switch 410 moves into position 18. The brush carriage is now restored to its 105 normal condition by means of a circuit from battery through the winding of power magnet 404, upper contact 414 (18), back contact of relay 402, back contact of relay 400 to ground. When the brush carriage reaches normal a circuit is closed from battery 110 through the winding of relay 400, right contact 415 (18), and brush 435 to ground. Relay 400 operates and opens the circuit of the power magnet 404, stopping the brush carriage. Relay 400 also closes a circuit from ground through its front contact, right contact 413 (18), winding of sequence switch 410 to battery, driving said sequence switch into its normal position, position 1. It will be noted that the trip spindle of 115 the final selector restores to normal as soon as sequence switch 410 reaches position 12 over a circuit from battery through the magnet 405, upper contact 431 (12+1), interrupter springs 407, 408 to ground. All 120 apparatus taken in connection with estab-

lishment of a call from the subscriber's line 100 to the subscriber's line 430 local to the second exchange has thus been restored to its normal condition.

5 *Establishment of a call to a distant office.*

Consideration will next be given to the establishment of a connection from the calling subscriber's line 100 to a called subscriber's line 430 which terminates in an office distant from the office containing the group selector 180. In this case the selector switch 180 chooses an outgoing two-wire trunk leading to the distant called office and there terminating in a group selector switch 330.

The initial operations following the registration of the call proceed in substantially the same manner as already discussed heretofore, the register sender 101, however, taking a somewhat different setting in view of the fact that a call of a different class is being made. Following the setting of the sender the group selector 108, 109 is positioned and an idle trunk 110, 111 leading to the second or tandem office is chosen. Thereafter the fundamental circuit is prepared as above explained and the group selector switch 180 is operated in its brush tripping movement to select a set of brushes having access to a level of trunks outgoing to the distant called office. These trunks are indicated by the terminals 155, 156, 157, 158, 159, 160, etc. It will be recalled that following the brush tripping movement of the switch 180 the sequence switch 120 advances from position 2 into position 3. In position 3 of the sequence switch the circuit already traced is closed for the power magnet 122 and the brush carriage commences to rotate advancing the tripped set of brushes 161, 162 and 163 over the terminals of the trunks leading to the distant office.

This time the first set of terminals in the level represent an outgoing trunk instead of being used for a discriminatory purpose as in the case of a level of local trunks. Therefore, the circuit previously traced for the relay 114 is now held open when the test brush 163 encounters the first test terminal in the level inasmuch as this terminal is connected to battery rather than being connected to the sequence switch contact 123. The brush carriage continues to rotate until the terminals of an idle trunk are reached, at which time a high potential is encountered by the test brush 163. A circuit is then closed from battery over test terminal 160, brush 163, upper left contact 132 (3), winding of relay 118 to ground. Relay 118 operates and closes a low resistance circuit through its right-hand winding and contact 134 to ground. The low resistance of the right-hand winding of relay 118 reduces the potential on terminal 160, rendering the trunk non-select-

able to other switches. Relay 118 also opens the circuit of relay 117 which in turn opens the power circuit causing the switch to come to rest. Relay 117 moves the sequence switch out of position 3 and into position 5. 70

While sequence switch 120 is passing through position 4 the circuit hereinbefore traced for relay 112 is held open due to the fact that relay 114 did not operate at the time the brushes of the switch passed over the first set of terminals in the level. Consequently, on an interoffice call both the relays 112 and 116 remain deenergized.

The fundamental circuit over which the sender 101 controls the selector switch 330 80 in the distant office is prepared in two sections with provision for repeating the impulses from one section of the circuit to the other. With sequence switch 120 in position 5 a circuit is closed from battery through 85 the winding of relay 117, upper left contact 135 (5), middle right back contact of relay 112 thence over the conductor 111, through the winding of stepping relay 102 and returning over conductor 110, upper contact 90 124 (1+13), upper left contact 128 (5+7), left back contact of relay 112 to ground. Relay 117 operates and locks in a circuit from battery through its winding, lower left contact 135 (5+13), outer right contact of 95 relay 117 and thence as previously traced over the circuit including the stepping relay 102 to ground on the left contact of relay 112. Relay 117 on operating closes a circuit from battery through its inner right 100 front contact, lower left contact 139 (5), winding of sequence switch magnet 120 to battery, driving said sequence switch into position 7. Relay 117 remains locked in the circuit traced in position 7 of the sequence 105 switch. The fundamental circuit interconnecting the switch 330 in the distant office and the switch 180 is established as follows: battery through the winding of relay 300, lower left contact 314 (1+1½), conductor 110 170, terminal 159, brush 162, left back contact of relay 113, outer right contact of relay 112, upper left contact 130 (6½+7), lower left contact 130 (1+17), winding of relay 115, conductor 178, left front contact of relay 117, conductor 179, upper right contact 125 (6½+7), brush 161, terminal 158, conductor 169, left contact 318 (1+2) to ground. Relay 300 becomes operated in this circuit and completes a circuit from ground through its right front contact, lower left contact 312 (1), upper right contact 312 (1+6), left-hand winding of relay 303, lower left contact 315 (1), left-hand winding of relay 301, lower left contact 321 (1), upper right contact 321 (1+4) to battery. Relays 301 and 303 attract their armatures and a circuit is closed from battery through the winding of sequence switch magnet 310, upper left contact 311 (1), front contact of re- 130

5 lay 303, right contact 318 ($1\frac{3}{4}+1$) to ground. Sequence switch 310 moves out of position 1 and into position 2 and relays 303 and 301 become deenergized. Relay 300 remains energized in position 2 of the sequence switch by means of a circuit from battery through its winding and left contact, conductor 331, lower right contact 322 (1 $\frac{3}{4}+2$) thence over the fundamental circuit as previously traced to ground.

The brush tripping magnet 304 is now energized by means of a circuit from battery through the winding of said magnet, lower left contact 332 (2), right front contact of relay 300 to ground. For each tripping position passed over by the spindle a circuit is closed from battery through the winding of relay 300, left contact of said relay, interrupter springs 306, 307 and 308 to ground. This circuit maintains the energization of relay 300, but causes the relay 115 in the other end of the fundamental circuit to be shunted. Relay 115 upon deenergizing closes a circuit from battery through the winding of relay 117, lower right contact 136 (7), back contact of relay 115, lower left contact 140 (7), inner right front contact of relay 117 to ground. This circuit maintains the energization of relay 117, but shunts out the stepping relay 102 at the sender 101. The stepping relay 102 in the well-known manner causes the advance of the corresponding register. This procedure continues, relay 115 being shunted for each tripping position passed over by the trip spindle of the switch 330 and in turn causing the shunting of relay 102 at the sender until the proper set of brushes has been selected. At this time the fundamental circuit is opened at the sender. As soon, following the opening of the fundamental circuit at the register sender in the originating office, as the interrupter springs 306 and 307 are opened the relay 115 becomes energized and in so doing opens the substitute holding circuit of relay 117. Relay 117 thereupon retracts its armatures and in turn opens the circuit including relays 115 and 300. These relays become deenergized and relay 300 by retracting its armatures opens the circuit of the trip spindle magnet 304. Relay 300 also closes a circuit from ground through its right back contact, lower left contact 311 (2+4), winding of sequence switch magnet 310 to battery. Sequence switch 310 leaves position 2 and on reaching position 3 a circuit is closed from battery through the winding of relay 300, upper right contact 314 (2+5), back contact of relay 303, back contact of relay 302, upper right contact 317 (23/4+9), lower right contact 317 (2+4), interrupter springs 307 and 308 to ground. Relay 300 operates and opens the circuit of sequence switch 310 causing the same to stop in position 3.

When relay 117 deenergizes at the completion of the brush tripping operation a circuit is closed from ground through the inner right back contact of said relay, lower right contact 139 (7), winding of sequence switch 120 to battery. Sequence switch 120 moves out of position 7 into position 8 where it remains until the switches are in condition for the next selective operation. With sequence switch 310 in position 3 a circuit is closed from battery through the winding of relay 300, upper right contact 314 (2+5), back contact of relay 303, back contact of relay 302, upper right contact 317 (2 $\frac{3}{4}$ +9), lower right contact 317 (2+4), springs 307 and 308 to ground. Relay 300 completes a circuit from battery through the winding of brush carriage power magnet 305, lower right contact 332 (3), right front contact of relay 300 to ground. The selected set of brushes 323, 324 and 325 are driven over the terminals of the bank in the trunk hunting movement. When an idle final selector switch is found a circuit is closed from battery through the winding of relay 401, and also in parallel from battery through contact 412, test conductor 328, brush 325, upper right contact 315 (3), right-hand high resistance winding of relay 303 to ground. Due to the presence of a high potential in this circuit test relay 303 is operated and opens the circuit of relay 300 which in turn deenergizes and opens the circuit of the power magnet 305. Relay 300 moreover completes a circuit from ground through its right back contact, lower left contact 311 (2+4), winding of sequence switch magnet 310 to battery, driving said sequence switch out of position 3 and into position 5. Relay 303 on operating closes the circuit over the test conductor through its left-hand low resistance winding, upper right contact 312 (1+6), upper left contact 312 (3+6), front contact of relay 303 thence to ground as previously traced through interrupter springs 307 and 308. This low resistance circuit reduces the potential on terminals of the trunk leading to the final selector to render said selector busy to other switches. As soon as sequence switch 310 reaches position 3 $\frac{3}{4}$ the circuit of relay 303 is modified to extend to ground at the right contact 318 (3 $\frac{3}{4}$ +8).

The fundamental circuit is now prepared for controlling the brush tripping operation of the final selector switch. When sequence switch 310 is in position 5 a circuit is closed from battery through the winding of relay 400, left contact 422 (1+5), conductor 328, brush 324, upper right contact 320 (5+9), lower left contact 320 (5), conductor 170, terminal 159, brush 162, left back contact of relay 113, outermost right contact of relay 112, lower right contact 126 (8+9), windings of relay 114, impedance coil 175, upper left contact 125 (8+8½), brush 161, terminal 120 125 130

nal 158, conductor 169, upper left contact 319 (5+9), upper right contact 319 (5), brush 323, conductor 326, left contact 421 (1+5) to ground. Relay 114 operates in 5 this circuit but due to the high resistance of the right-hand winding of relay 114, relay 400 does not receive sufficient current to energize. As soon as the sender 101 is in condition to control the next selective movement, a circuit is established from battery through the winding of relay 117, upper left contact 135 (8), middle right contact of relay 112 over the conductor 111 through the winding of the stepping relay 102 re- 10 turning by way of conductor 110, upper right contact 124 (1+13), lower right contact 128 (8+9) to ground at the contact of relay 114. Relay 117 completes a circuit from ground through its inner right front contact, lower left contact 139 (8), winding of sequence switch 120 to battery. Sequence switch 120 moves out of position 8 and into position 10. Relay 117 remains energized in position 10 in a locking circuit traceable 15 from battery through the winding of said relay, lower left contact 135 (5+13), outer right contact of relay 117, thence over the fundamental circuit as previously traced returning by way of conductor 110, upper right contact 124 (1+13), upper left contact 128 (8 $\frac{3}{4}$ +10) to ground at the left back contact of relay 112. When sequence switch 120 moves out of position 8 $\frac{1}{2}$ and into position 9, relay 114 becomes deenergized but 20 this relay does not release until after the upper left contact 128 is closed. With sequence switch 120 in position 10 and with relay 117 energized a circuit is now established from battery through the winding of relay 400 at the final selector switch thence as previously traced over the lower talking conductor to brush 162, left-hand contact of relay 113, outermost right contact of relay 112, upper left contact 130 (9 $\frac{1}{2}$ +10), lower left contact 130 (1+17), winding of relay 115, conductor 178, left front contact of relay 117, conductor 179, upper right contact 125 (9 $\frac{1}{2}$ +10), brush 161, thence over the upper talking conductor to ground at contact 421. Due to the low resistance of relay 115, the relay 400 at the final switch becomes energized. Relay 400 causes the advance of the sequence switch 410 into position 2 where the brush tripping spindle is operated in the manner hereinbefore explained. 25 At each brush tripping movement of the switch the relay 115 is shunted and this relay in turn causes the shunting of relay 102 at the sender 101. When the proper set of brushes have been reached in the operation of the final selector, the sender opens the fundamental circuit and shortly thereafter relays 117, 115 and 400 become deenergized. Relay 400 advances the sequence 30 switch 410 into position 5, while relay 117 completes a circuit as follows: ground through the inner right back contact of relay 117, lower right contact 139 (10), winding of sequence switch magnet 120 to battery. Sequence switch 120 moves out of position 10 into position 11. 35 Immediately after sequence switch 120 reaches position 11 a circuit hereinbefore traced is closed including relay 400 at the final switch and relay 114 at the group selector 180. Relay 114 operates but relay 400 remains deenergized. Relay 114 closes the circuit above traced for relay 117 including the stepping relay 102 of the sender. Relay 117 closes a circuit through its inner right front contact and the lower left contact 139 (11) for driving sequence switch 120 into position 13. In position 13, the relay 117 remains energized in the locking circuit as previously traced through the lower left contact 135 (5+13) and the outer right contact of relay 117. As soon as sequence switch 120 reaches position 12 $\frac{1}{2}$ on its way to position 13 a circuit is closed from battery through the winding of relay 400 thence over the lower talking conductor hereinbefore traced, left back contact of relay 113, outermost back contact of relay 112, upper left contact 130 (12 $\frac{1}{2}$ +13), lower left contact 130 (1+17), winding of relay 115, conductor 178, left contact of relay 117, conductor 179, upper right contact 125 (12 $\frac{1}{2}$ +13), thence to ground at contact 421. The closure of this circuit occurs before sequence switch 410 has time to reach position 5 and hence relay 400 becomes operated to open the driving circuit of the sequence switch permitting it to stop in said position. The units selecting operation now takes place at the final switch at the end of which the fundamental circuit is opened and relays 115, 117 and 400 become deenergized. Relay 117 closes the circuit from ground through its inner right back contact, lower right contact 139 (13), winding of sequence switch magnet 120 to battery driving said sequence switch out of position 13 into position 14. 40 45 50 55 60 65 70 75 80 85 90 95 100 105 110 115 120 125

Immediately following the units selecting operation the register sender 101 is detached and a source of battery current at the group selector switch at said originating office is connected to the outgoing trunk line 110, 111 provided the calling subscriber has not replaced his receiver on the switchhook. The relay 114 is connected across the trunk 110, 111 as previously explained and energizes in series with the battery source at the originating office. Relay 114 closes a circuit from ground through its contact, lower left contact 136 (14+16), winding of relay 117 to battery. Relay 117 completes a circuit from ground through its inner right front contact, lower left contact 139

(14+15), winding of sequence switch magnet 120 to battery driving said sequence switch into position 16. When sequence switch 410 of the final selector moves out of position 5, contact 412 is opened and hence the resistance in series with the test circuit is increased. This increase of resistance causes the relay 303 to be deenergized, relay 401 remaining operated. Relay 303 on retracting its armature completes a circuit from battery through the winding of relay 300, upper right contact 314 (2+5), back contact of relay 303, right contact 318 (3 3/4+8) to ground. Relay 300 operates and closes a circuit from ground through its right front contact, upper right contact 311 (5+8), winding of the sequence switch magnet 310 to battery. Sequence switch 310 leaves position 5 and moves into position 7. Since the calling subscriber still has his receiver off the switchhook relay 114 is energized and consequently relay 117 is energized and sequence switch 120 is standing in position 16. Hence, when sequence switch 310 reaches position 6 a circuit is closed from battery through the winding of relay 116, lower right contact 127 (16), outermost right contact of relay 112, left contact of relay 113, brush 162, terminal 159, conductor 170, upper left contact 322 (6+9), through the windings of relay 301, lower right contact 321 (6+9), upper left contact 321 (6+9), conductor 169, terminal 158, brush 161, lower left contact 125 (16+17), impedance coil 119, conductor 173 to ground at the contact of relay 114. Relay 301 operates and closes a circuit from battery through the winding of relay 300, lower right contact 313 (6+9) to ground at the contact of relay 301. Relay 300, therefore, remains energized and holds the circuit of sequence switch 310 closed whereby said sequence switch moves over positions 7 and 8 and into position 9. Relay 300 remains energized in position 9 of the sequence switch. As sequence switch 310 enters position 6 the circuit of relay 401 is extended by way of conductor 327 directly to ground at the lower right contact 315 (6+9) thereby shunting out the test relay 303.

Following this the final selector switch tests the called subscriber's line, applies ringing current thereto if same is idle and the circuit is finally prepared for talking. When the called subscriber answers a circuit is closed from battery through the winding of relay 302, lower right contact 320 (9), upper right contact 320 (5+9), brush 324 and thence over the loop of the called subscriber's line 430 and returning to brush 323, impedance coil 309, upper right contact 352 (9+10) to ground at the right front contact of relay 300. Relay 302 becomes energized and shunts out the

right hand resistance winding of relay 301. The circuit including relay 301 may now be traced over conductor 170, upper left contact 322 (6+9), left hand winding of relay 301, upper left contact 317 (9+10), upper right contact 317 (2 3/4+9), front contact of relay 302, lower right and upper left contacts 321 (6+9) and thence over conductor 169. Relay 116 which was included in series with the high resistance winding of relay 301 does not operate until said high resistance winding is removed from the circuit at the response of the called subscriber. Relay 116 now attracts its armature and in so doing shunts out the right hand high resistance winding of relay 114 excluding the same from the circuit leading back to the originating office. This decrease in the resistance may be utilized as heretofore observed for supervision or for line registration or for any other desired purpose.

At the end of conversation the subscribers replace their receivers on the switchhooks and relays 114 and 302 become deenergized. Relay 114 opens the circuit of relay 117 which in turn closes the circuit for driving sequence switch 120 into position 17. Thereafter the restoration of the group selector switch 180 is substantially the same as above described.

When sequence switch 120 leaves position 16 relay 301 at the distant office becomes deenergized and in so doing opens a circuit of relay 300. Relay 300 completes a circuit from ground through its right back contact, lower left contact 311 (9+18), winding of sequence switch magnet 310 to battery. Sequence switch 310 leaves position 9. On reaching position 15 1/2 a circuit is closed from battery through the winding of relay 300, upper right contact 314 (15+18), back contact of relay 303, back contact of relay 302, upper right contact 317 (15 1/2+16), lower right contact 317 (11+16), springs 307 and 308 to ground. Relay 300 opens the circuit of sequence switch 310 which stops in position 16. Here a circuit is closed from battery through the trip spindle magnet 304, lower left contact 332 (16), front contact of relay 300 to ground. The trip spindle restores and on reaching normal the circuit of relay 300 is opened by springs 307 and 308. Relay 300 opens the circuit of magnet 304. Relay 300 also closes a circuit including the lower left contact 311 for driving sequence switch 310 out of position 16.

On reaching position 17 3/4 sequence switch 310 completes a circuit from battery through the winding of relay 300, upper right contact 314 (15+18), back contact of relay 303, right contact 318 (17 3/4+1) to ground. Relay 300 operates and opens the circuit of sequence switch 310 causing the same to

stop in position 18. The brush carriage restores in this position by means of a circuit from battery through the winding of power magnet 305, lower right contact 332 5 (18), right front contact of relay 300 to ground. When the brush carriage reaches its normal position a circuit is closed from battery through the brush 333; upper left-hand contact 316 (17+18 $\frac{1}{4}$), lower left contact 10 316 (10+8), right-hand winding of relay 303 to ground. Relay 303 operates and opens the circuit of relay 300 and this relay becomes deenergized and opens the circuit of the power magnet 305. Relay 300 15 also closes a circuit from ground through its right back contact, lower left contact 311 (9+18), winding of sequence switch 310 to battery, driving said sequence switch out of position 18 and into position 1.

20 The restoration of the final selector switch shown in Fig. 4 takes place in substantially the same manner as previously discussed.

What is claimed is:

1. In a telephone exchange system, a plurality of calling lines, a plurality of trunk lines of different classes, a selective switch, means for operating said switch to select one of said trunks to extend a connection thereover, an automatic switch for further extending said connection, a sender common to said plurality of calling lines, a control circuit including the selected trunk for controlling said automatic switch, and means rendered effective by said selective switch 25 according to the class of the trunk selected for determining the character of said control circuit.

2. In a telephone exchange system, a plurality of calling lines, a plurality of trunk lines of different classes, a selective switch, means for operating said switch to select one of said trunks to extend a connection thereover, an automatic switch for further extending said connection, a sender common to said plurality of calling lines, a control circuit including the selected trunk, means controlled by said sender over the control circuit for operating said automatic switch, and means rendered effective by said selective switch 40 according to the class of the trunk selected for determining the character of said control circuit.

3. In a telephone exchange system, a plurality of calling lines, a plurality of trunk lines of different classes, a selective switch, means for operating said switch to select one of said trunks to extend a connection thereover, an automatic switch for further extending said connection, a sender common to said plurality of calling lines, a control circuit including the selected trunk for controlling the operation of said automatic switch, and means individual to the selective switch 45 rendered effective by such switch according to the class of the trunk selected for

determining the character of said control circuit.

4. In a telephone system, a plurality of trunk lines of different classes, a selective switch, means for operating said switch to 50 select one of said trunks to extend a connection thereover, automatic switches, one in which each of said trunks terminates, means for operating said automatic switches to further extend a connection, a control circuit including the selected trunk for controlling the corresponding automatic switch, and means rendered effective by said selective switch in its operation of selecting a trunk of any class for determining the character of the control circuit. 75

5. In a telephone exchange system, a plurality of calling lines, a plurality of trunk lines of different classes, a selective switch, means for operating said switch to select one of said trunks to extend a connection thereover, an automatic switch for further extending said connection, a sender common to said plurality of calling lines, a control circuit extending from the sender to said automatic switch and including the selected trunk for controlling the movement of said automatic switch, a repeater, and means rendered effective by said selective switch in its selective operation for inserting said repeater in the control circuit. 80

6. In a telephone exchange system, a plurality of calling lines, a plurality of trunk lines of different classes, a selective switch, means for operating said switch to select one of said trunks to extend a connection thereover, an automatic switch for further extending said connection, a sender common to said plurality of calling lines, a control circuit extending from the sender to said automatic switch and including the selected trunk for controlling the movement of said automatic switch, a repeater individual to the selective switch, and means rendered effective by said selective switch in its selective operation for inserting said repeater in the control circuit. 100

7. In a telephone exchange system, a plurality of calling lines, a plurality of trunk lines of different classes, a selective switch, means for operating said switch to select one of said trunks to extend a connection thereover, an automatic switch for further extending said connection, a sender common to said plurality of calling lines, a control circuit extending from said sender to the automatic switch and including the selected trunk, means for sending impulses over the control circuit for determining the operation of the automatic switch, and means rendered effective by the selective switch in its operation for repeating the impulses sent over said control circuit when a trunk of a certain class is selected. 115

8. In a telephone exchange system, a trunk 120

125

130

line of a given class, a second trunk line of a different class, a selective switch, means for operating said switch to select either of said trunks to extend a connection thereover, automatic switches, one in which each of said trunks terminates, a sender, a control circuit extending from the sender to the corresponding automatic switch when a connection is extended over said first trunk, means 10 for sending impulses over said control circuit between the automatic switch and the sender for determining the movement of such automatic switch, a second control cir-

cuit extending between the other automatic switch and the sender when a connection is extended over said second trunk, means for creating impulses in said second control circuit, and means rendered effective by the selective switch for repeating such impulses between the automatic switch and the sender for determining the movement of said second automatic switch. 15 20

In witness whereof, I hereunto subscribe my name this 30th day of December, A. D., 1921.

LIPA POLINKOWSKY
